(57) **CLAIM**

The ornamental design for a car jump starter with air compressor, as shown and described.

DESCRIPTION

FIG. 1 is a front, left and top perspective view of a car jump starter with air compressor, showing our design.

FIG. 2 is a rear, right and bottom perspective view thereof.

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

FIG. 9 is an enlarged view of portion 9 shown in FIG. 1; and,

FIG. 10 is an enlarged view of portion 10 shown in FIG. 2.

The broken lines in the drawings illustrate the portions of the car jump starter with air compressor, which form no part of the claimed design.

1 Claim, 10 Drawing Sheets
